(57) CLAIM

The ornamental design for a flask with pants pocket, as shown and described.

DESCRIPTION

FIG. 1 is a top perspective view of a flask with pants pocket;

FIG. 2 is a front view thereof;

FIG. 3 is a back view thereof;

FIG. 4 is a left side view thereof;

FIG. 5 is a right side view thereof;

FIG. 6 is a top side view thereof; and,

FIG. 7 is a bottom side view thereof.

The dashed lines show stitching in a material that surrounds the outside of the flask. The stitching defines a pattern that emulates a rear pants pocket, such as a rear jeans pocket. The dashed lines are not to be considered “broken lines” for unclaimed subject matter.
